FRED HARRIS LYNDS, OF NORTH ATTLEBORO, MASSACHUSETTS, ASSIGNOR TO WHITING & DAVIS COMPANY, A CORPORATION OF MASSACHUSETTS.

MESH MACHINE.

Application filed July 2, 1925. Serial No. 41,111.

This invention relates to machines for uniting pieces of mesh fabric, and more particularly that kind of fabric known as fish-scale mesh. This mesh consists of a plurality of rings formed of pieces of wire bent to appropriate form, which are joined together to produce a fabric by means of spiders of metal which have legs passing through the individual links. Each link in the fabric is entered by the legs of four different spiders, but no two links are directly intermeshed.

This fish-scale mesh is produced in a number of different machines of well-known construction, and is used for many different purposes, as, for instance, in the manufacture of ladies' hand-bags. In such use the piece of mesh is cut to appropriate form, and then connected to a bag frame in any suitable manner. The pieces of mesh which are used to form the body of the bag are ordinarily of irregular outline and it frequently happens that there are scrap pieces of mesh left from the main body after the bag pattern has been cut, which usually have to be discarded. This adds considerably to the cost of the mesh, since it involves a direct loss of material, time, etc.

The object of the present invention is to provide a machine by which two pieces of fish-scale mesh may be united and by the operation of the machine a number of pieces of scrap mesh as above referred to, may thus be connected together so as to form a larger piece of mesh which is of a size sufficient for commercial purposes.

A machine which embodies the principles of the present invention includes means for supporting the two pieces of mesh which are to be joined together with their free edges placed parallel a short distance apart. The free rings along the margin of each piece of mesh are separated a distance equal to the distance between the rings in the completed mesh, and appropriate devices are provided for advancing the two pieces of mesh with a step-by-step movement past suitable tools. A strip of spider stock is fed to these tools and the individual spiders are cut successively from the end of the strip stock, the legs of the spiders bent so that they may enter the marginal rings of the pieces of mesh, and then the legs, after such insertion, are bent inwardly so as to grip the rings. When this

series of operations has been completed, the two pieces of mesh are advanced by another step, the spider stock is also fed forwardly by the desired amount, and the cycle of operations is repeated.

As the machine continues to operate, a succession of spiders is inserted in the two pieces of mesh in such manner as to connect the marginal rings, and when the whole series of rings along the edges of the two pieces of mesh have thus been treated, a single piece of mesh is produced in which no line of junction is apparent. This piece of mesh consequently, may be used for ordinary commercial purposes, for which either of the two pieces which have been combined to produce it would be of insufficient size.

In the accompanying drawings, I have illustrated a machine embodying the principles of the invention, and in these drawings,

Fig. 1 is a side view in elevation with certain parts shown in section;

Fig. 2 is an end view of the machine, looking toward the left in Fig. 1;

Figs. 3, 4, and 5 are sectional views taken on the lines 3—3, 4—4, and 5—5 respectively of Fig. 1;

Fig. 6 is a plan view of the table on which the pieces of mesh are supported;

Fig. 7 is an end view of the parts illustrated in Fig. 6;

Figs. 8, 9, and 10 are sectional views through the spider-cutting and forming mechanism, showing the parts in three distinct stages in their operation;

Fig. 11 is a sectional view on the line 11—11 of Fig. 9;

Fig. 12 is a view in section of the parts by which the spider is inserted through the rings of the mesh;

Fig. 13 is a similar view showing the parts at a different stage in the operation; and

Fig. 14 is a plan view of four links or rings, showing the manner in which these links are secured together by means of a spider.

Referring now to these drawings, the machine is seen to consist of an upright body member 20 mounted on a foot 21 in any appropriate place. Extending from the upright is a bracket 22 in which are mounted certain slides, presently to be described. A plate 23 extends laterally from the upright

member and carries an end plate 24, the latter also containing slides, presently to be described.

Mounted in suitable bearings 25 and 26 in brackets extending upwardly beyond the end of the standard 20, is the main drive shaft 27, carrying a pulley 28 on one end by which the machine may be driven from any suitable source of power. This shaft carries a bevel gear 29, meshing with a similar gear 30 on a shaft 31 which is carried in bearings 32 and 33, the first bearing being mounted in a suitable bracket 34 on top of the plate 23, while the second bearing is mounted in a similar bracket 35 at the top of the end plate 24.

The standard 20 is cut away near its lower end, as at 36, to form an aperture through which extends a table 37, this table supporting the two pieces of mesh which are to be united. As shown more clearly in Fig. 6, the pieces of mesh consist of rings 38, arranged in rows extending at right angles to each other, and spiders 39 are provided for connecting groups of four rings each spider having four legs, each of which enters one of these rings and is then bent inwardly so as to hold the ring tightly. It will be seen from Fig. 6 that each ring is entered by a single leg of four different spiders. The table 37 is provided with a series of ribs spaced apart the distance between the centers of the rings of adjacent rows, and the two pieces of mesh to be united, designated at 41 and 42, are laid on the table with their rows of links lying on top of the ribs. The spiders, as shown in Fig. 7, extend downwardly below the plane of the rings and the inwardly turned legs of the spiders, as at 43, enter between the adjacent ribs. As the two pieces of mesh are fed with a step-by-step motion, the ribs serve to keep the marginal rings in the proper alignment.

Mounted in suitable brackets 44 on the standard 20 is a vertical rock shaft 45, which is surrounded by a sleeve 46. The shaft carries a collar 47 at its upper end, having an arm 48 provided with a roller 49 bearing against the face of the cam 50 on the shaft 27. Beneath this collar 47 is a similar collar 51 having a similar arm 52 carrying a roller 53 which bears against the opposite face of the cam 50. The cam is provided with cam grooves in which the rollers extend, and as the main shaft 27 is rotated the rock shaft and the sleeves are given appropriate rocking movements by the action of the cam. Just above the lower bracket 44 is a collar 54 on the shaft 45 provided with an arm 55 in the end of which is pivotally mounted a lever 56 which is secured at its other end to a slide 57 mounted in suitable guide-ways in the bracket 22. Within this slide is a second

slide 58 to the rear end of which is secured a lever 59 pivotally secured at its other end to an arm 60, rigidly secured to a collar 61 on the sleeve 46. The arms 54 and 60 are provided with springs 62 secured at one end to the rigid, upright member 20 and tending to hold these arms in their forward position in which the slides are advanced.

Mounted in the end of the slide 57 in suitable guide-ways, is a vertical slide 63, formed with an opening 64 through which extends the end of the inner slide 58. This inner slide is made with beveled surfaces 65 at its end and the opening in the vertical slide 63, through which the end of the slide 58 extends, is similarly beveled. The form and proportion of the parts is such that when the inner slide 58 is moved relatively to the outer slide 57, the coacting inclined surfaces on the inner slide and on the vertical slide will cause an up-and-down movement of the vertical slide, depending on the direction in which the inner slide is moved. At its upper end the vertical slide carries a die member 66, illustrated more clearly in Fig. 12 and Fig. 13. This die member has four up-standing prongs 67, spaced so as to enter four adjacent rings in a completed part of the mesh, and its upper face is hollowed out centrally as at 68 for a purpose presently to be described. The table 37 is slotted in its forward edge, as at 69, so that the die member 66 may project upwardly through this slot.

When the machine is to be started the two pieces of mesh to be united are placed on the table in the relation indicated in Fig. 6, and the inner slide 58 is given a movement which causes the vertical slide 63 to be drawn downwardly. The inner and outer slides 58 and 57 now move as one to the left, as shown in Fig. 1, then the inner slide is given a movement which causes the vertical slide to move upwardly so that the prongs 67 enter four rings, two on each piece of mesh, as shown in Fig. 6. With the vertical slide in its uppermost position, both inner and outer slides are now moved forward until the vertical slide is in the position shown in Fig. 1, when the four rings entered by the prongs of the die member on the vertical slide will be in proper position to be acted on. The feeding of the two pieces of mesh is thus brought about by the engagement of the prongs 67 on the die member 66 with the rings along the edge of the mesh, and in order to insure that the mesh will be fed evenly without buckling there are provided presser feet 70, pivotally mounted on a pin 71 in a bracket 72 secured to the lower end of the end plate 24. A spring 73 normally tends to swing these pressure members about their pivot pin so as to raise them free of the mesh. In this bracket, however, is mounted a pin 74 pro-

- vided with a handle 75, this pin having a half-round portion which bears against the upper surface of the presser feet. By moving the handle to different positions of adjustment, the pin may be made to bear against the pressure feet so as to overcome the action of the spring 73 and cause the pressure feet to bear more or less firmly against the upper faces of the pieces of mesh.
10. The feeding operation brought about by the action of the three slides causes the mesh to be advanced with a step-by-step movement, and at each period of rest in the step-by-step movement four of the rings are entered and joined by means of a spider. The mechanism by which this spider is inserted in position and its legs clinched, includes means for advancing a strip of spider material, cutting and forming mechanism, and means coacting with the die member 66 for inserting the legs of the spider through the proper rings and then bending these legs inwardly so as to clinch the spider in position.
15. The stock from which the spiders are cut is shown at 76, and consists of a strip of flat metal notched along its edges and provided with central apertures. By cutting this stock so as to sever it at each central aperture, a spider having a central portion and four legs is formed. This stock is fed from the left in Fig. 1, and passes beneath a friction presser member 77 mounted in a suitable guide-way in the plate 23, and normally pressed downwardly by a spring 78. An L-shaped aperture 79 is formed in the plate 23 and the presser member has a pin 80 which enters this aperture. At its lower end the presser bears against the stock and forces it against the face of a bracket 81, secured to the plate 23. With this arrangement, when the pin is in the upright portion of the aperture 79 the spring is free to force the presser member against the stock, and grip it between the end of the presser member and the bracket. The pin, however can be raised into the flat portion of the aperture thus relieving the stock of pressure.
20. Moving in a suitable guide-way formed in the lower end of the plate 24 is a slide 82, shown more clearly in Fig. 4. At the rear end there is mounted in this slide an upright standard 83, which is provided with an adjustment screw 84. The standard lies in a slot in the end of the slide, and the adjustment screw permits the standard to be moved in and out of the slot with a fine adjustment. In the upper end of the standard is pivoted a pawl 85, carried on an eccentric pin having a slotted head 86. This pin is so formed that a flat tool may be inserted in the slot and the head of the pin turned, whereupon the pawl may be moved laterally with respect to the standard. The pawl at its forward end carries a tooth 87. The strip
25. stock 76, passing from beneath the presser foot 77, extends through the end plate 24, entering a guide-way 88, above which the pawl lies. A spring 89 tends to force the pawl downwardly and as the slide 82 is reciprocated in a horizontal direction by suitable means, the pawl enters one of the central apertures in the stock on its movement toward the left, and as the pawl is moved to the right it engages the stock and advances it a distance corresponding to the extent of movement of the slide. The pawl consequently acts as a feeding means for the stock.
30. The slide 82 is provided with an aperture 90, formed in one face, in which is received the rounded head of a lever 91, mounted at the end of a rock shaft 92, encircled by a coil spring 92' and carried in suitable bearings 93 and 94 on the side of the end plate 24. At its upper end the shaft carries a collar 95, provided with a cam follower 96, which is held against the face of a cam 97 mounted on the shaft 31 by means of the spring 92', one end of which is secured to the shaft, the other end to the bearing 93. As the shaft 31 rotates, the vertical rock shaft 92 is rocked in its bearings, and this causes the slide 82 to reciprocate in a horizontal plane. The slide carried a pin 98, serving as a die member, and the upper face of the guide-way in which the slide moves is notched, as at 99, to receive the die member on the movement of the slide to the left, as shown in Fig. 1.
35. Mounted in suitable guide-ways in the end plate 24, is an L-shaped slide 100, which carries at its upper end a roller 101, bearing against a cam 102, on the shaft 31. A spring 103 enters a slot in the L-shaped slide, and tends to force it upwardly so that the roller will bear against the face of the cam. Mounted in the small leg of the L is a tubular sleeve 104, which is formed with a cutting edge at its lower end cooperating with a cutting plate 105, mounted in the lower end of the end plate 24 above the reciprocating slide 82. The end of the sleeve lies in a suitable guide-way formed in the lower end of the plate 24, directly above the guide-way in which the slide 82 moves. Within the sleeve is a plunger 106, mounted in the end of a second slide 107, the upper end of which carries a cam roller 108, bearing against a cam 109 on the shaft 31. A spring 110 encircling the rod and bearing at its upper end against the slide 107, acts to hold the slide in its uppermost position, so that the cam roller will bear against the face of the cam.
40. The operation of the parts just described is as follows: At each operation of the slide 82, the strip stock is fed forward by the length of one spider. Then at the proper instant, when the stock has come to rest, the

slide 100 is moved down by its cam 102, the second slide 107 being given a similar movement, but being so placed relatively to the first slide that the end of the rod 106 lies spaced inwardly from the end of the sleeve 104. At this time the slide 82 is moved to a position in which the die member 98 is in registry with it, lying beneath the end of the strip stock. The downward movement 10 of the sleeve 104 causes one spider to be cut from the end of the strip, the parts occupying the position illustrated in Fig. 8. Upon the further downward movement of the sleeve, the legs of the spider which has been 15 cut from the end of the stock are forced around the pin 98. In such movement, since the bending action is caused by the inner edge of the sleeve 104, the legs of the spider will bear against the inner surface of the 20 sleeve. The sleeve with its rod now moves upwardly to the position indicated in Fig. 10, carrying the spider 111 with it. The slide 82 is now moved inwardly as soon as the legs of the spider have cleared the end 25 of the pin 98. During this movement the two pieces of mesh have been advanced by the feeding mechanism so that the rings to be entered by the legs of the spider are in proper position on the die member 66. The 30 sleeve 104 now moves downwardly beyond the end of the slide 82 which has been retracted out of the way until the lower end of the sleeve is in position directly above the end of the die member 66. The legs of 35 the spider 111 now lie in registry with the prongs 67 on the die member, each of these legs being positioned so as to enter a ring. The second slide 107 is now moved downwardly by its cam forcing the rod 106 downwardly through the sleeve so as to force the spider 111 out of the sleeve.

Each leg of the spider now enters one of the rings along the line of union, and by the continued downward movement of 45 the rod, the legs, having entered the rings, are forced inwardly by the action of the dished surface 68 on the end of the die member 66 until the legs occupy the position designated 112 in Fig. 13. When this movement has been completed the spider occupies a position relative to the four rings, as shown in Fig. 14. The sleeve and rod are now raised out of coaction with the die member 66, and when they have reached a 50 position above the strip stock, the stock is fed by the amount of another spider. During this movement the slides 57, 58, and 63 have moved so as to disengage the rings entered by the spider, and to engage another 55 group of rings, which are then placed in position by the action of the slides. The cycle of operations is now repeated, and is continuous throughout the length of the 60 pieces of mesh.

65 It will be seen that in this machine the

two pieces of mesh to be joined are fed forwardly in proper alignment with a step-by-step movement, and in each period of rest of the movement a spider which has previously been cut from the stock and acted upon so that its legs extend at right angles to the plane of the spider, is advanced so as to insert its legs through the rings to be connected. The legs of the spider are then turned inwardly so as to grip the rings firmly, and thereafter the piece of mesh is advanced by another step, during which operation the strip stock is fed, the spider formed and held ready to be inserted through the next group of rings. The action of the machine is positive, and the several groups of mechanism are properly timed and co-ordinated so that the cycle of operations is carried on in part synchronously and in part consecutively, so that the desired uniting operation may be continued for an indefinite period. By the use of the machine the pieces of mesh which would otherwise be discarded as scrap, may be connected together, and the single piece of mesh formed by their union is similar in all respects to the mesh as produced on the mesh-making machines. The machine is simple in operation, and the uniting of the two pieces of mesh is relatively inexpensive since the operation of the machine does not require expert attention. Also, the spiders which are used do not have to be separately produced, and fed to the machine from a magazine, as is frequently the case in machines in which such spiders are employed. On the contrary, the present machine includes suitable tools by which the spiders are formed from the strip stock, interlinked with the rings at the edges of the two pieces of mesh, and then closed.

I claim:

1. A machine for uniting pieces of mesh fabric consisting of rings connected by spiders, which comprises a support for holding two pieces of mesh to be united with their edges parallel but separated, means for holding a supply of spider material, tools operable to form spiders, insert their legs through a plurality of rings at the edges of the pieces of mesh, and turn the legs inwardly to secure the rings, and power-driven devices for giving the tools and the pieces of mesh a relative movement during which the pieces of mesh are maintained in a plane at all times, and for operating the tools.

2. A machine for uniting pieces of mesh fabric consisting of rings connected by spiders, which comprises a support for holding two pieces of mesh to be united with their edges parallel but separated, means for holding a supply of spider material, tools operable to form spiders, insert their legs through a plurality of rings at the edges of the pieces of mesh, and turn the legs inward-

- ly to secure the rings, power-driven devices for giving the tools and the pieces of mesh a step-by-step relative movement during which the pieces of mesh are maintained in a plane at all times, and for operating the tools in the periods of rest of the step by step movement.
3. A machine for uniting pieces of mesh fabric consisting of rings connected by spiders, which comprises a support for holding the two pieces of mesh to be united with their edges parallel but separated, means for holding a supply of spider material, tools operable to form spiders, insert their legs through a plurality of rings at the edges of the pieces of mesh, and turn the legs inwardly to secure the rings, means including one of the tools for causing a relative movement of the pieces of mesh and the remaining tools, and power-driven devices for operating the tools.
- 10 4. A machine for uniting pieces of mesh fabric consisting of rings connected by spiders, which comprises a support for holding the two pieces of mesh to be united with their edges parallel but separated, means for holding a supply of spider material in the form of a strip, tools operable to cut spiders from the strip, insert the legs of each spider thus severed through a plurality of rings at the edges of the pieces of mesh, and turn these legs inwardly to secure the rings, means adjacent the tools for maintaining the pieces of mesh in a plane, and power-driven devices for moving the tools and the pieces of mesh relatively and for operating the tools.
- 15 5. A machine for uniting pieces of mesh fabric consisting of rings connected by spiders, which comprises a support for holding the two pieces of mesh to be united with their edges parallel but separated, means for holding a supply of spider material in the form of a strip, a pair of tools operable to form spiders and insert their legs through a plurality of rings at the edges of the pieces of mesh, a third tool engaging the said rings and movable to advance these rings into position to receive the spider and thereafter cooperating with one of the tools first mentioned to close the inserted legs to secure the rings, and power-driven devices for operating the tools in their proper sequence.
- 20 6. A machine for uniting pieces of mesh fabric consisting of rings connected by spiders, which comprises a support for holding the two pieces of mesh to be united with their edges parallel but separated, means for holding a supply of spider material in the form of a strip, a pair of co-acting tools operable to cut a spider from the end of the strip and to bend the legs of the spider substantially at right angles to the plane of the spider, one of these tools being also adapted to insert the legs of this spider through a plurality of rings at the edges of the pieces of mesh, a third tool co-acting with the tool last mentioned for bending inwardly the legs of the spider so inserted to secure the rings entered, means adjacent the third tool for maintaining the pieces of mesh in a plane, means for giving the tools and the pieces of strip material a relative movement to cause the material to be placed in position to be acted on by the tools, and power-driven devices for moving the tools and the pieces of mesh relatively and for operating the tools in their proper sequence.
- 25 7. A machine for uniting pieces of mesh fabric consisting of rings connected by spiders, which comprises a support for holding the two pieces of mesh to be united with their edges parallel but separated, means for holding a supply of spider material, tools operable to form spiders, insert their legs through a plurality of rings at the edges of the pieces of mesh, and turn the legs inwardly to secure the rings, one of these tools being also operable to advance the pieces of mesh into position to be acted on, and power-driven devices for operating the tools.
- 30 8. A machine for uniting pieces of mesh fabric consisting of rings connected by spiders, which comprises a support for holding the two pieces of mesh to be united with their edges parallel but separated, means for holding a supply of spider material in the form of a strip, a pair of tools operable to form spiders and insert their legs through a plurality of rings at the edges of the pieces of mesh, a third tool engaging the said rings and movable to advance these rings into position to receive the spider and thereafter cooperating with one of the tools first mentioned to close the inserted legs to secure the rings, and power-driven devices for operating the tools in their proper sequence.
- 35 9. A machine for uniting pieces of mesh fabric consisting of rings connected by spiders, which comprises a support for holding the two pieces of mesh to be united with their edges parallel but separated, means for holding a supply of spider material in the form of a strip, a pair of tools operable to form spiders from the said material and to insert the legs of each spider through a plurality of rings at the edges of the pieces of mesh, a third tool operable to engage a plurality of rings at the edges of the piece of mesh and to advance the pieces of mesh to place these rings in position to receive the legs of a spider, this tool thereafter cooperating with the tools first mentioned to turn the legs of the spider inwardly to secure the rings, means for maintaining the pieces of mesh in a plane adjacent the point of action of the tools, and power-driven devices for operating the tools.
- 40 10. In a machine for uniting pieces of mesh fabric consisting of rings connected by

spiders, the combination of a support for holding the two pieces of mesh to be united with their edges parallel but separated, a tool for inserting the legs of a spider through a plurality of rings at the edges of the pieces of mesh, a second tool cooperating therewith to turn the inserted legs inwardly to secure the rings thus entered, the second tool being movable to advance the pieces of mesh to place the rings in position to receive the legs of the spiders, and means for operating the tools.

11. In a machine for uniting pieces of mesh fabric consisting of rings connected by spiders, the combination of a support for holding the two pieces of mesh to be united with their edges parallel but separated, a tool for inserting the legs of a spider through a plurality of rings at the edges of the pieces of mesh, this tool lying at one side of the pieces of mesh, a second tool lying on the opposite side of the pieces of mesh and operable to engage a plurality of rings in the pieces of mesh, to move these rings into spider-receiving position, and in cooperation with the first tool to turn the inserted legs of the spider inwardly to secure the rings so entered, and means for operating the tools.

12. In a machine for uniting pieces of mesh fabric consisting of rings connected by spiders, the combination of a support for holding the two pieces of mesh to be united in a plane with their edges parallel but separated, a tool operable to insert the legs of a spider through a plurality of rings at the edges of the pieces of mesh, a second tool movable to engage a plurality of rings of the pieces of mesh, to advance these rings to spider-receiving position, and in cooperation with the first tool to turn inwardly the legs of the spider inserted through the said rings to secure the rings, means adjacent the tools for holding the pieces of mesh in a plane during their movement, and means for operating the tools.

13. In a machine for uniting pieces of mesh fabric consisting of rings connected by spiders, the combination of a support for holding the two pieces of mesh to be united with their edges parallel but separated, a pair of tools cooperating to form spiders and to bend the legs of these spiders to give the spiders a staple form, one of the tools being operable to insert the legs of the spider through a plurality of rings at the edges of the pieces of mesh, and a third tool operable to engage a plurality of rings at the edges of the pieces of mesh, to move these rings to a position to receive the legs of the spider, and in cooperation with the inserting tool to turn the legs of the spider inwardly to secure the rings.

14. In a machine for uniting pieces of mesh fabric consisting of rings connected by spiders, the combination of a support for

holding the two pieces of mesh to be united in a plane with their edges parallel but spaced apart, a pair of slides reciprocating parallel to the plane of the support and relatively movable, and a third slide carried by the slides first mentioned and movable at right angles to the plane of the pieces of mesh by the relative movement of the said slides, the third slide carrying means for entering a plurality of rings at the edges of the pieces of mesh, whereby upon the simultaneous movement of the slides first mentioned, the pieces of mesh will be advanced.

15. In a machine for uniting pieces of mesh fabric consisting of rings connected by spiders, the combination of a support for holding the two pieces of mesh to be united in a plane with their edges parallel but spaced apart, a pair of slides reciprocating parallel to the plane of the support, a third slide carried by the slides first mentioned and reciprocable at right angles to these slides by their relative movement, a die member carried by the third slide and provided with means for engaging a plurality of rings at the edges of the pieces of mesh to cause the latter to be advanced upon the simultaneous movement of the first two slides, and a tool co-acting with the die member for inserting the legs of a spider through a plurality of rings at the edges of the pieces of mesh and bending the inserted legs inwardly to secure these rings.

16. In a machine for uniting pieces of fabric consisting of rings connected by spiders, the combination of a support for holding the two pieces of mesh to be united with their edges parallel but spaced apart, a pair of slides reciprocable parallel to the plane of the support and relatively movable, cam surfaces formed on one of these slides, a third slide mounted in guide-ways in the other of the slides, and having surfaces contacting with the said cam surfaces, whereby upon the relative movement of the first two slides the third slide may be reciprocated in a direction at right angles to their direction of movement, and a die member carried by the third slide and provided with a plurality of prongs adapted to enter a plurality of rings at the edges of the pieces of mesh and thus to cause the pieces of mesh to be advanced on the support upon the simultaneous movement of the first two slides.

17. In a machine for uniting pieces of fabric consisting of rings connected by spiders, the combination of a support for holding the two pieces of mesh to be united with their edges parallel but spaced apart, a pair of slides reciprocable parallel to the plane of the support and also relatively movable, cam surfaces formed on one of these slides, a third slide mounted in guide-ways in the other of the slides, and having surfaces con-

- facting with the said cam surfaces, whereby upon the relative movement of the first two slides the third slide may be reciprocated in a direction at right angles to their direction of movement, a die member carried by the third slide and provided with a plurality of prongs adapted to enter a plurality of rings at the edges of the pieces of mesh and thus to cause the pieces of mesh to be advanced 10 on the support upon the simultaneous movement of the first two slides, and a tool movable toward and away from the die member and operable to insert the legs of a spider through the rings entered by the die member and in co-action with the die member to cause these legs to be bent inwardly to secure the rings.
18. In a machine for uniting pieces of fabric consisting of rings connected by spiders, the combination of a support for holding the two pieces of mesh to be united in a plane with their edges parallel but spaced apart, a slide reciprocable toward and away from the support and carrying means for entering a plurality of rings at the edges of the pieces of mesh, and means for reciprocating this slide toward and away from the pieces of mesh and for moving the slide bodily parallel to the plane of the support whereby the slide may act to advance the pieces of mesh on the support.
19. In a machine for uniting pieces of fabric consisting of rings connected by spiders, the combination of a support for holding the two pieces of mesh to be united in a plane with their edges parallel but spaced apart, a slide reciprocable toward and away from the support and carrying means for entering a plurality of rings at the edges of the pieces of mesh, and a pair of slides relatively movable to advance the first slide toward and away from the pieces of mesh, and movable simultaneously to carry the first slide bodily in a direction parallel to the plane of the support whereby the said means on the third slide acts to advance the pieces of mesh on the support.
20. In a machine for uniting pieces of fabric consisting of rings connected by spiders, the combination of means for holding a supply of spider material in the form of a strip, a die member operable to cut a spider from the end of the strip, a second die member cooperating with the first to bend the legs of the spider so cut substantially at right angles to the plane of the spider, a support for holding the two pieces of mesh to be united with their edges parallel but spaced apart, means associated with the first die member for inserting the bent legs of the spider through a plurality of rings at the edges of the pieces of mesh, a third die member cooperating with the said means for turning the inserted legs of the spider inwardly to secure the rings en-
- tered, the third die member being movable to engage the successive groups of rings and to move these rings into position to receive the legs of the spider, and means for operating the tools and the said inserting means.
21. In a machine for uniting pieces of fabric consisting of rings connected by spiders, the combination of means for holding a supply of spider material in the form of a strip, a reciprocable sleeve having a cutting edge for cutting a spider from the end of the strip, a die member cooperating with the sleeve and with it serving to bend the legs of the said spider at right angles to the plane of the latter, a support for holding the two pieces of mesh in a plane with their edges parallel but spaced apart, a plunger within the sleeve operating to insert the legs of the spider acted upon through a plurality of rings at the edges of the pieces of mesh, a die member cooperating with the plunger and serving to turn the inserted legs inwardly to secure the rings entered, the said die member being operable to engage successive groups of rings at the edges of the pieces of mesh and to move the pieces of mesh to place these rings in position to receive the legs of the spider, and means for operating the said die members.
22. In a machine for uniting pieces of fabric consisting of rings connected by spiders, the combination of means for holding a supply of spider material in the form of a strip, a die member, a support for holding the two pieces of mesh in a plane with their edges parallel but spaced apart, a sleeve having a cutting edge, means for advancing the sleeve to cut a spider from the end of the strip and to cause the sleeve and die member to co-act to bend the legs of the said spider at right angles to the plane of the spider and for then advancing the sleeve to a position close to the plane of the pieces of mesh, a plunger within the sleeve operable to cause the legs of the spider to enter a plurality of rings at the edges of the pieces of mesh, a second die member co-acting with the plunger and adapted to bend the legs inserted inwardly to secure the rings so entered, the second die member being operable to engage successive groups of rings at the edges of the piece of mesh and to advance the pieces of mesh to bring these rings into position to receive a spider, and means for operating the die members and the plunger.
23. In a machine for uniting pieces of fabric consisting of rings connected by spiders, the combination of a support for holding the two pieces of mesh to be united in a plane with their edges parallel but spaced apart, a die member having means for entering a plurality of rings at the edges

of the pieces of mesh and movable to advance the pieces of mesh with a step-by-step movement, means for holding a supply of spider material in the form of a strip, a second die member lying beneath the spider at the end of the strip, a tool movable toward and away from the strip and carrying means for cutting a spider from the end of the strip and, in co-action with the second die member, bending the legs of the spider at right angles to the plane of the latter, this tool being operable thereafter to insert the legs of the spider through a plurality of rings at the edges of the pieces of mesh and, in co-action with the first die member, to bend these legs inwardly to secure the rings so entered.

24. In a machine for uniting pieces of fabric consisting of rings connected by spiders, the combination of a support for holding the two pieces of mesh to be united in a plane with their edges parallel but spaced apart, a die member movable toward and away from the pieces of mesh and also in a direction parallel to the plane in which they lie, this die member carrying means for entering a plurality of rings at the edges of the pieces of mesh whereby the pieces of mesh are moved on their support by the die member, means for holding a supply of spider material in the form of a strip, a slide reciprocable parallel to the plane of the strip and carrying means for engaging the strip and a die member lying beneath the end of the strip, a pair of slides movable toward and away from the strip and also relatively movable, a sleeve having a cutting edge carried by one of these slides, a plunger within the sleeve carried by the other slide, and means for moving the first slide to cause the sleeve to cut a spider from the strip and then to cooperate with the second die member to cause the legs of this spider to be bent at right angles to the plane of the spider, the said means then acting to move the sleeve with the spider mounted in it to a position directly above a plurality of rings at the edges of the pieces of mesh, and means for moving the slide carrying the plunger relative to the sleeve to cause the plunger to force the spider out of the sleeve and to insert its legs through a plurality of rings at the edges of the pieces of mesh, the plunger also co-acting with the die member first mentioned near the end of its movement to turn these legs inwardly to secure the rings so entered.
25. In a machine for uniting pieces of fabric consisting of rings connected by spiders, the combination of means for holding a supply of spider material in the form of a strip, a slide reciprocated parallel to the plane of the strip, means carried by the slide for engaging the strip and advancing it with the slide, a die member carried with the slide

lying beneath the end spider of the strip, and means adapted to cut the end spider from the strip and, in co-action with the die member, to bend the legs of this spider at right angles to the plane of the latter.

26. In a machine for uniting pieces of fabric consisting of rings connected by spiders, the combination of means for holding a supply of spider material in the form of a strip, means for advancing the strip with a step-by-step movement, a pair of tools operating at each period of rest of the movement for cutting a spider from the end of the strip and bending the legs of this spider at right angles to its plane, a support for holding the pieces of mesh to be united in a plane with their edges parallel but spaced apart, means for inserting the legs of the spider acted upon by the tools through a plurality of rings at the edges of the pieces of mesh, and a die member cooperating with the said means to bend the inserted legs inwardly to secure the rings so entered, the said die member being movable to engage a plurality of rings at the edges of the pieces of mesh and to advance the pieces of mesh to bring these rings into position to receive the legs of the spider.

27. In a machine for uniting pieces of fabric consisting of rings connected by spiders, the combination of means for holding a supply of spider material in the form of a strip, a reciprocable slide carrying means for engaging and advancing the strip with the slide and also carrying a die member lying beneath the end of the strip, and a tool co-acting with the die member and movable to sever a spider from the end of the strip and bend the legs of this spider at right angles to its plane.

28. In a machine for uniting pieces of fabric consisting of rings connected by spiders, the combination of means for holding a supply of spider material in the form of a strip, a reciprocable slide carrying means for engaging and advancing the strip with the slide and also carrying a die member lying beneath the end of the strip, a tool operable to sever the spider from the end of the strip and, in co-action with the die member, to bend the legs of this spider at right angles to its plane, a support for holding the two pieces of mesh to be united in a plane with their edges parallel but spaced apart, means for advancing the tool and the spider toward the pieces of mesh on the support, a plunger within the tool operable to insert the legs of the spider through a plurality of rings at the edges of the pieces of mesh, and a second die member adapted to cooperate with the plunger to bend the inserted legs of the spider inwardly to secure the rings entered.

In testimony whereof I affix my signature.
FRED HARRIS LYNDS.
